UNITED STATES PATENT OFFICE.

ARTHUR P. CONANT, OF FORT THOMAS, KENTUCKY, ASSIGNOR TO THE WADSWORTH WATCH CASE COMPANY, OF DAYTON, KENTUCKY, A CORPORATION OF KENTUCKY.

DESIGN FOR A WATCHCASE APPENDAGE.

Application filed November 21, 1924. Serial No. 11,435. Term of patent 14 years.

To all whom it may concern:

Be it known that I, ARTHUR P. CONANT, a citizen of the United States, residing at Fort Thomas, in the county of Campbell and State of Kentucky, have invented a new, original, and ornamental Design for Watchcase Appendages, of which the following is a specification, reference being had to the accompanying drawing, forming part thereof.

Fig. 1 is a side elevation of a watchcase

appendage embodying my design, its relation to the watch case and crown being indicated by a conventional showing thereof by dotted lines; and

Fig. 2 is an edge view thereof.

I claim:

The ornamental design for a watchcase appendage, substantially as shown.

ARTHUR P. CONANT.
